(57) **CLAIM**

The ornamental design for a furniture connector, as shown and described.

DESCRIPTION

FIG. 1 is a first perspective view of my design for a furniture connector;

FIG. 2 is a top plan view of my design for a furniture connector;

FIG. 3 is a bottom plan view of my design for a furniture connector;

FIG. 4 is a left side view of my design for a furniture connector;

FIG. 5 is a right side view of my design for a furniture connector;

FIG. 6 is a front elevational view of my design for a furniture connector;

FIG. 7 is a rear elevational view of my design for a furniture connector;

FIG. 8 is a second perspective view of my design for a furniture connector;

FIG. 9 is a third perspective view of my design for a furniture connector; and,

FIG. 10 is a fourth perspective view of my design for a furniture connector.

1 Claim, 10 Drawing Sheets
